Specification for Design.

Patented Apr. 15, 1919.

Application filed November 12, 1914. Serial No. 871,793. Term of patent 14 years.

To all whom it may concern:

Be it known that I, FRANK S. HYATT, a citizen of the United States, residing at Brooklyn, in the county of Kings and State of New York, have invented a new, original, and ornamental Design for Can-Tops, of which the following is a specification, reference being had to the accompanying drawing, forming part thereof, in which—

Figure 1 is a plan view of a can top showing my new design.

Copies of this patent may be obtained for five cents each, by addressing the "Commissioner of Patents, Washington, D. C."

Fig. 2 is a front elevation of the same.

Fig. 3 is a side elevation.

I claim:

The ornamental design for a can top, as shown.

FRANK S. HYATT.
